FIG. 1.

FIG. 2.

Inventor
Gustave M. Minton
By his Attorney
Charles G. Nensley

UNITED STATES PATENT OFFICE.

GUSTAVE M. MINTON, OF NEW YORK, N. Y.

DESIGN FOR A SMOKER'S TRAY.

58,926.

Specification for Design.

Patented Sept. 6, 1921.

Application filed October 21, 1919. Serial No. 332,311. Term of patent 3½ years.

To all whom it may concern:

Be it known that I, GUSTAVE M. MINTON, a citizen of the United States, residing in the city, county, and State of New York, have invented a new, original, and ornamental Design for a Smoker's Tray, of which the following is a specification, reference being had to the accompanying drawing, forming part thereof.

I claim:

The ornamental design for a smoker's tray, as shown.

GUSTAVE M. MINTON.
